(57) **CLAIM**

The ornamental design for a sandal upper, as shown and described.

DESCRIPTION

FIG. 1 is a perspective view of a sandal upper showing my new design;

FIG. 2 is a side view thereof;

FIG. 3 is an opposite side view thereof;

FIG. 4 is a front elevation view thereof;

FIG. 5 is a rear elevation view thereof;

FIG. 6 is a top view thereof; and,

FIG. 7 is a bottom view thereof.

The broken lines applied to the sandal upper in FIGS. 1-7 represent claimed stitching. Broken lines in or showing the sole of the sandal, including surfaces of the insole and the outsole, in FIGS. 1-7, are for environmental purposes only and form no part of the claimed design. The claimed design does not include any part of the sole.
